United States Patent Office

Des. 202,219
Patented Sept. 7, 1965

202,219

BOTTLE

Archie G. Drummond, Jr., Wantagh, Harold J. Vanderhyde, Merrick, and Alban Gifford Jackson, New York, N.Y., assignors to Anderson Clayton & Co., Dallas, Tex., a corporation of Delaware

Filed Feb. 4, 1964, Ser. No. 78,506

Term of patent 14 years

(Cl. D58—6)

FIG. 1

FIG. 2

FIG. 4

We claim:

The ornamental design for a bottle, as shown and described.
